UNITED STATES PATENT OFFICE.

AUGUST SCHWARZSCHILD AND NELSON GREENFIELD, OF NEW YORK, N. Y.

DESIGN FOR CONFECTIONERY.

SPECIFICATION forming part of Design No. 18,206, dated March 27, 1888.

Application filed February 23, 1888. Serial No. 265,048. Term of patent 3½ years.

To all whom it may concern:

Be it known that we, AUGUST SCHWARZSCHILD and NELSON GREENFIELD, citizens of the United States, residing in the city, county, 5 and State of New York, have invented and produced a new and original Design for Gum, Candy, or Confectionery, of which the following is a specification, reference being had to the accompanying drawings, forming part 10 thereof.

This design consists in the shape or representation of candy, gum, or confectionery in the 15 form of a stick flat on the under side, as at a, and rounded on the upper side, as at b, half-round in cross-section, and having one end slightly enlarged laterally, as at c, and having formed in the upper surface of the enlarged 20 end a rectangular depression, d.

Having thus described our new design, what we claim is—

A design for gum, candy, or confectionery herein shown and described, consisting of a 25 stick half-round in cross-section, with one end enlarged laterally and a rectangular depression in the said enlarged end of the stick.

AUGUST SCHWARZSCHILD.
NELSON GREENFIELD.
